DESIGN FOR A LADY'S HAT

Isidor Melamed, New York, N. Y., assignor to Newmarket Hat Company, Inc., New York,
N. Y., a corporation of New York

Application November 16, 1936, Serial No. 65,943

Term of patent 3½ years

To all whom it may concern:

Be it known that I, Isidor Melamed, a citizen of the United States, residing at 1420 Clay Avenue, Bronx county, city and State of New York, have invented a new, original, and ornamental Design for Lady's Hat, of which the following is a specification, reference being had to the accompanying drawing forming a part thereof.

In the drawing:

Fig. 1 is a perspective view of my new design
taken from the rear.

Fig. 2 is a perspective view taken from the front.

I claim:

The ornamental design for a lady's hat substantially as shown.

ISIDOR MELAMED.
